UNITED STATES PATENT OFFICE

ALFRED J. FLAUDER, OF TRUMBULL, CONNECTICUT, ASSIGNOR TO WEIDLICH STERLING SPOON CO., OF BRIDGEPORT, CONNECTICUT, A PARTNERSHIP CONSISTING OF LOUIS WEIDLICH, OF STRATFORD, CONNECTICUT, FRANK B. WEIDLICH, OF NEW YORK, N. Y., AND WILLIAM WEIDLICH, OF BRIDGEPORT, CONNECTICUT

DESIGN FOR A SPOON OR ANALOGOUS ARTICLE

Application filed March 26, 1931. Serial No. 39,248. Term of patent 7 years.

To all whom it may concern:

Be it known that I, ALFRED J. FLAUDER, a citizen of the United States, and a resident of Trumbull, in the county of Fairfield and State of Connecticut, have invented a new, original, and ornamental Design for a Spoon or Analogous Article, of which the following is a specification, reference being had to the accompanying drawings, forming a part thereof, and in which—

Fig. 1 is a front elevation of a spoon showing my new design;

Fig. 2 is a rear elevation of the same; and Fig. 3 shows a cross section of the handle portion of the spoon, taken on line 3—3 of Fig. 1.

I claim:

The ornamental design for a spoon or analogous article substantially as shown.

Signed at Bridgeport in the county of Fairfield and State of Connecticut, this 24th day of March, 1931.

ALFRED J. FLAUDER.
